UNITED STATES PATENT OFFICE.

PAUL JOSEPH LEMMER, OF DANBURY, CONNECTICUT.

TOILET-SEAT COVER.

Application filed December 21, 1921. Serial No. 523,892.

To all whom it may concern:

Be it known that I, PAUL J. LEMMER, a citizen of the United States, residing at Danbury, in the county of Fairfield, State 5 of Connecticut, have invented a new and useful Toilet-Seat Cover; and I do hereby declare the following to be a full, clear, and exact description of the invention, such as will enable others skilled in the art to which 10 it appertains to make and use the same.

The invention relates to toilet seat covers and has for its object to provide a device of this character adapted to be disposed on a toilet seat in such a manner as to prevent 15 contact of the body of the user with the toilet seat or with the hopper.

Also to form the cover from relatively pliable material, such for instance as paper and to provide the cover with members ex- 20 tending downwardly into the hopper and in position where they will be engaged by water during a flushing operation in such a manner that the cover will be dragged into the hopper, and from its position on the seat.

25 A further object is to provide a toilet seat cover comprising a member adapted to be disposed on the toilet seat and having an opening registering with the opening in the seat, said member at its rear side being split 30 and provided with a downwardly extending water engaging drag, by means of which drag the cover is pulled into the hopper during a flushing operation.

With the above and other objects in view 35 the invention resides in the combination and arrangement of parts as hereinafter set forth, shown in the drawings, described and claimed, it being understood that changes in the precise embodiment of the invention may 40 be made within the scope of what is claimed without departing from the spirit of the invention.

In the drawings:

45 Figure 1 is a perspective view of a conventional form of hopper showing a seat cover applied thereto.

Figure 2 is a vertical transverse sectional view through the upper end of the hopper, the toilet seat and the cover.

50 Figure 3 is a bottom perspective view of the cover.

Figure 4 is a detail perspective sectional view on an enlarged scale through one side of the cover showing a portion of the seat 55 and hopper in dotted lines.

Referring to the drawings, and more particularly to Figures 1 to 4 inclusive, the numeral 1 designates a conventional form of hopper and 2 a hopper seat disposed thereon. The hopper 1 is flushed adjacent its 60 rear side 3 by means of a down rush of water from the flushing pipe 4, which discharges water through the discharge pipe 5. The toilet seat cover 6 comprises a substantially annular member 7 formed from paper or thin cardboard, said annular member being split at its rear end and having its ends 8 and 9 overlapped, as clearly shown in Figure 3, the purpose of which will presently appear. Secured to the under side of the annular member 7 and extending downwardly 65 through the opening 2^a of the toilet seat 2, and into the mouth of the hopper is a skirt 10, which prevents contact of the body of the user with the inner edge of the seat 2 or with the inner side of the hopper. The skirt 10 is preferably formed from thin paper such for instance as tissue paper and is preferably adhesively joined to the under 70 side of the annular member 7 by means of integral spaced flanges 11 carried by the skirt, which flanges are adhesively joined to the annular member. Secured to the skirt 120 adjacent the end 8 of the cover 6 is a 75 downwardly extending drag member 12, which member extends downwardly into the chamber of the hopper and at a point where water during a flushing operation after leaving the discharge port 5, will engage the drag member 12 and drag the end 8 of the 80 annular member 7 into the hopper where it will be engaged by the down flowing water and the seat cover as a whole dragged into the hopper. By providing this dragging means it will not be necessary for the operator to touch the cover and it will be seen that if the operator should forget to remove the cover, the flushing operation would remove the same.

From the above it will be seen that a toilet 95 seat cover is provided, which cover will prevent contact of the user's body with the seat of the hopper, and one wherein during a flushing operation of the hopper the cover will be dislodged from its position on the 100 seat by the down rushing water.

The seat cover 6 may be formed from any kind of material, paper or cloth, and may be paraffined or otherwise water proofed, thereby preventing the user from coming into con- 110

tact with any moisture on the seat or hopper. The invention having been set forth what is claimed as new and useful is:—

A toilet seat cover formed from pliable material and having a centrally disposed opening, said cover being split, thereby forming adjacent ends a downwardly extending annular member carried by the inner edge of the cover and having a split in registration with the split in the cover and a downwardly

extending water engaging member carried by one of the adjacent ends of the cover and downwardly extending annular member adjacent the split and adapted to be engaged by water during a flushing operation where-¹⁵ by the cover will be moved with its ends in, advance of the main body of the cover.

In testimony whereof I have signed my name to this specification.

PAUL JOSEPH LEMMER.
